UNITED STATES PATENT OFFICE

167,913

SHOULDER BAG

Charles Stark, Kew Gardens Hills, N. Y.

Application May 16, 1952, Serial No. 19,733

Term of patent 7 years

(Cl. D87—3)

To all whom it may concern:

Be it known that I, Charles Stark, a citizen of the United States of America, and a resident of Kew Gardens Hills, county of Queens and State of New York, have invented a new, original, and ornamental Design for a Shoulder Bag, of which the following is a specification, reference being had to the accompanying drawing forming a part hereof, in which—

Fig. 1 is a side elevation of a shoulder bag embodying my design.

Fig. 2 is an end view thereof.

Fig. 3 is a top plan view.

Fig. 4 is a bottom view.

Fig. 5 is a cross-sectional view taken on the line 5—5 of Fig. 1.

I claim—

The ornamental design for a shoulder bag, as shown.

CHARLES STARK.
